Primary Examiner — George D. Kirschbaum*Assistant Examiner* — Darryl J Dardenne(74) *Attorney, Agent, or Firm* — Dunlap Bennett & Ludwig, PLLC(57) **CLAIM**

The ornamental design for an inverted bottle holder, as shown and described.

DESCRIPTION

FIG. 1 is a perspective view of an inverted bottle holder, showing my new design;

FIG. 2 is a front elevation view thereof, the rear elevation view being a mirror image thereof;

FIG. 3 is a right side elevation view thereof, the left side elevation view being a mirror image thereof;

FIG. 4 is a top plan view thereof;

FIG. 5 is a bottom plan view thereof; and,

FIG. 6 is a perspective view thereof, showing the new design in use.
The broken lines showing a bottle in FIG. 6 depicts environmental subject matter that forms no part of the claimed design.**1 Claim, 4 Drawing Sheets**(56)
